In Germany April 26, 1934

3 Claims. (Cl. 88—14)

This invention relates to a method and apparatus for recording the temperatures of single spots in temperature fields.

The temperature of radiant hot bodies can be recorded by pyrometers recording the total radiation and by pyrometers recording part of the radiation. The pyrometers recording the total radiation always require a large radiating area and in the case of technical instruments recording can be effected as low as 400° C. In the case of pyrometers recording only part of the radiation and also in the case of the modern color pyrometers, the temperatures of smaller areas, in certain cases even of points, can be recorded. This, however, can only be effected by means of the visible radiation so that those instruments fail to work at temperatures below 700° C.

The present invention is based on the discovery that the principle of the process of Serial No. 654,952, filed Feb. 1, 1933, may also be advantageously applied to record temperatures as low as 400° C. without visible radiation for proportionally smaller areas. U. S. Patent application Serial No. 654,952, filed Feb. 1, 1933, describes a process in accordance with which such temperature fields are rendered visible by optically projecting the bodies on an excited luminous screen, the image being produced by the extinction of the luminescence of the screen caused by the infra-red rays radiated from the hot body. In accordance with the present invention it becomes possible to record the temperature directly on comparing the extinction or blackening of the luminous screen with a standardized grey filter.

The accompanying drawing illustrates by way of example in Figure 1 a sectional view and in Figure 2 a cross section of a device for carrying out the process of the present invention. Referring to the drawing, in a casing 1 there is fixed upon a hollow shaft 2 a white plane disc 3, for instance, a white cardboard or a white painted tin disc, upon which by a lens 4 the body, the temperature of which is to be recorded, is optically projected. The image appears on the disc in reflected light as if on a ground glass screen and may be focused by means of a mirror 5 and an eye-piece 6. In the optical axis of the lens 4 there is on the disc 3 a circle 18, of for instance 2 mm. diameter, which serves to focus the apparatus on that spot the temperature of which is to be recorded. The opposite part of the disc is covered with a layer of a luminescent substance 7 which has in the center at the same

distance from the axis as the circle on the lower part of the disc a hole of equal size behind which, at a short distance, connected by an arm 19 with the shaft 2 there is a smaller disc 8, which preferably is a little larger than the hole 20 in the disc 3. Initially by means of an incandescent lamp 9 through a corresponding filter 10 the substance in the layer 7 and also the substance on the disc 8 are excited to luminescence until the highest possible luminescence is attained. Then the disc 3 is rotated by means of the shaft 2 so that the part covered with the luminescent substance takes the place of the free uncovered part. By this rotation a standardized grey filter 11 fixed upon a glass plate 22 slides between the two luminescent plates 7 and 8. The grey filter 11 ends in a screen 23 which, in its normal position lies behind the circle 18. To the shaft 2 there is further connected on the same side as the luminescent surface of the disc 3 a black filter 13 through which only infra red rays penetrate and which, on the rotation of the shaft by means of handle 21, comes into the beam of the lens 4. The infra red rays passing through the lens 4 and having penetrated the filter 13 more or less extinguish the luminescence of the luminescent plate 7, so that viewed through the eye-piece 6 there is visible on the disc 3 covered with a luminescent substance 7 a corresponding greyish tinted image of the hot object. After a certain time, which is established in each case for a definite range of temperature, a screen 15, firmly attached to a shaft 14 passing through the hollow shaft 2 is moved by means of a handle 16 to a position in front of the lens and thereby the radiation is screened off. During that time the hole 20 in the luminescent area 7 appears black, since the luminescent substance 8 is screened off by means of the screen 23. On turning back the grey filter 11 by means of the slide 17, until the tint of the un-extinguished luminescent substance 8 corresponds exactly to the tint of the surroundings of the hole, that is to say the hole in the luminescent substance 7 disappears optically, the position of the grey filter 11 or its slide 17 which is attached to the outside of the casing for moving the grey filter and which bears a mark, indicates a value for the extinction caused by the infra red rays and thus a value for the strength of these rays, that is to say for the temperature of the body optically screened off at this spot. Since the grey filter and the mark have been standardized the temperature of the viewed spot of the hot body can be read from the position of the slide 17. On

turning back the disc 3 into the exciting position the grey filter 11 upon the glass plate 22 is likewise turned back by means of the pin 12 into the initial position.

5 Since the extinction of the luminescent substance 8 at a temperature of the radiant body of 400° C. after a few minutes shows a blackness sufficient for recording the temperature of the hot body a convenient recording up to this temperature is rendered possible.

Further, since the blackening of the excited luminescent substance by the infra red rays increases with the passage of time it becomes possible by shortening the time of extinction also to 15 record higher temperatures.

I claim:—

1. Method of measuring or indicating the temperature of spots on the surface of a hot object having a temperature below the limit of visibility 20 which comprises exciting a luminescent surface to luminescence, optically projecting an image of the object upon one portion of excited luminescent surface for a predetermined length of time by means of the infra-red rays emitted by said 25 object while excluding said radiation from a further portion of excited luminescent surface adjacent to said first portion, and measuring the difference in luminosity between the luminescent surface upon which the image has been projected 30 and the luminescent surface from which the radiation has been excluded by extinguishing the difference in luminosity by means of a standardized gray wedge, whereby the position of the gray wedge is a measure of the difference in luminosity 35 and therefore of the temperature of the corresponding spot on the object.

2. Apparatus for measuring or indicating the temperature of spots on the surface of a hot object having a temperature below the limit of visibility comprising a casing, at least one layer of 40 luminescent substance arranged in the interior of

the casing, a light source adapted to excite said substance into luminescence when the substance is exposed thereto, means for interrupting the exposure of the luminescent substance to the light source, optical means for projecting an image of the object by means of infra-red rays radiated therefrom upon the luminescent substance, a screen for excluding radiation from a portion of the luminescent substance during said projection, a gray wedge mounted for movement across the 10 portion of luminescent substance covered by said screen, means for replacing said screen by said gray wedge, and optical means for observing said gray wedge in juxtaposition to the luminescent substance upon which the image has been projected. 15

3. Apparatus for measuring or indicating the temperature of spots on the surface of a hot object having a temperature below the limit of visibility comprising a casing, a screen rotatably positioned adjacent one wall of the casing, said screen having on one portion a surface of luminescent material with a hole in approximately the center thereof and upon a diametrically opposite portion a circle at the same distance from the axis of 20 rotation of the screen as the hole, a second screen positioned behind said hole and having a surface of luminescent material at least as large as the hole, a standardized gray filter wedge and a protective screen positioned between said first named 25 screens and mounted for movement between the hole and the second screen, a light source adapted to excite the luminescent material, means for rotating the first named screen to expose the luminescent material separately to said light source and to infra-red radiation from the object, and optical means for observing the gray filter wedge through said hole in the first named 30 screen. 35
